(57) **CLAIM**

The ornamental design for a spoon rest, as shown and described.

DESCRIPTION

FIG. 1 is a perspective view of a spoon rest, showing our new design;

FIG. 2 is a front elevational view thereof;

FIG. 3 is a top plan view thereof;

FIG. 4 is a side elevational view thereof; and,

FIG. 5 is a rear elevational view thereof.

The dotted-line disclosure of elements in the views is for illustrative purposes only and forms no part of the claimed design.
